UNITED STATES PATENT OFFICE

OAK LANDAW, OF NAPPANEE, INDIANA, ASSIGNOR TO MUTSCHLER BROS. CO., OF NAPPANEE, INDIANA

TABLE

Application filed May 19, 1930. Serial No. 458,565.

The invention relates to tables, and particularly to tables of the extension leaf type, and has for its object to provide a table of this character in which the extension leaves 5 are positioned beneath the table top in parallel relation thereto when in retracted inoperative position.

A further object is to provide a table of this character provided with a table top having depending side flanges within which the extension leaves are adapted to be nested when in retracted position, said top being tilttable relative to the table frame to permit withdrawal of the leaves to operative extended position.

A further object is to provide a table of this character having extension leaves adapted to be locked in retracted position and means for automatically projecting said 20 leaves to operative extended position upon release of the means locking said leaves in retracted position.

A further object is to provide a table of this character having its top flexibly connected to 25 the table frame and controlled by guide means permitting only tilting of the top relative to the frame and preventing simultaneous equal upward movement of all points of the top relative to the frame.

30 A further object is to provide a table of this character having means carried by the top for locking the extension leaves in retracted position, means for automatically projecting the leaves to operative extended position upon predetermined shifting of the table top to release the locking means, and means for guiding the shifting of the top in the predetermined manner.

With the above and other objects in view, 40 the invention resides in the combination and arrangement of parts as hereinafter set forth, shown in the drawings, described and claimed, it being understood that changes in the precise embodiment of the invention may be 45 made within the scope of what is claimed without departing from the spirit of the invention.

In the drawings:

Figure 1 is a perspective view of the table 50 showing the leaves extended in dotted lines.

Figure 2 is a fragmentary side view of the table.

Figure 3 is a fragmentary end view of the table showing a portion thereof in section and showing the table top tilted and the extension leaves extended in dotted lines. 55

Figure 4 is a bottom plan view of the table showing one of the leaves in extended position.

Figure 5 is a longitudinal vertical sectional view taken on line 5—5 of Figure 3. 60

Figure 6 is a transverse vertical sectional view taken on line 6—6 of Figure 5.

Figure 7 is a fragmentary vertical sectional view taken on line 7—7 of Figure 5. 65

Figure 8 is a perspective view of the tilting controlling block and pin.

Figure 9 is a fragmentary vertical sectional view taken on line 9—9 of Figure 6. 70

Referring to the drawings, which illustrate the preferred embodiment of the invention, the numeral 10 designates a table frame comprising end rails 11, side rails 12 and legs 13. The upper portion of the end of each side rail 12 is cut away at 14, and mounted centrally in said cut-away portions 14 and extending transversely of the table frame between the opposite side rails are guide members 15. Guide members 15 are preferably T-shaped the stem of the T being supported by said side rails and the upper surfaces of the guide members being substantially level with the top of the side and end rails of the table frame. Mounted on the table frame is a table top 16, preferably of conventional sheet metal construction, and having flanges 17 depending from its perimeter in the conventional manner; said flanges receiving a supporting frame 18 therein which includes a central longitudinal cleat 19. At 75

each end of the table top a headed pin 20 depends vertically from the cleat 19 and passes through an aperture 21 formed in the guide member 15 therebeneath, Figure 9, said aperture being of a size to permit the pin to have a slight lateral movement as well as free longitudinal movement therein. Springs 22 are carried by cleat 19 and are connected to the end rails 11 adjacent the lower edges thereof. The springs 22 and pins 20 form the sole connection between the table top and table frame; 80 85 90 95 100

the pins serving to correctly position the table top on the frame and to limit the upward movement which the top may have relative to the frame, and the springs acting against upward movement of the frame relative to the frame.

On both sides of the guide members 15 are disposed L-shaped bars 23 adapted for longitudinal sliding movement relative to and guided by said guide members 15, said bars 23 extending through the cut-away portions 14 of the side rails of the frame. Supporting frames 24, carried by the under sides of guide members 15 and projecting laterally therefrom, support the bars 23 in operative horizontal position. Mounted on the outer ends of bars 23 at the opposite sides of the table frame are extension leaves 25, said leaves being of a length less than the inner dimensions of the supporting frame 18 and of a width less than the distance between the cleat 19 and the supporting frame whereby the extension leaves may be nested within the depending flanges of the table top and so held in retracted position. Springs 26 extend between the inner ends of the bars 23 and the opposite side of the table frame, said springs acting to force said bars and extension leaves outwardly of the table top into extended position. Stops 27 are carried by the bars 23 to limit the outward movement of the bars and extension leaves relative to the table top whereby said leaves will not be projected outwardly beyond operative extended position by springs 26. At the center of the inner side of each end rail and near the lower edge thereof is mounted a V-shaped guide block 28, having its lower point cut off, and above block 28 a pin 29 is secured to cleat 19 in vertically depending relation, said pin 29 having at its lower end a perpendicularly bent hook portion 30 disposable beneath said block. When the table is in its normal position with the extension leaves 25 in retracted position, the table top telescopes and rests upon said leaves, and the depending flanges 17 of the top, into which said leaves nest, lock the leaves in retracted position against the action of the springs 26; the springs 22 drawing the table top downwardly into bearing contact with the leaves. Upward tilting movement of one side of the table top against the action of springs 22 releases one of the extension leaves from its telescoped interlocked relation with the top; and said leaf is then automatically projected outwardly of the frame by its cooperating springs 26. The outward movement of said leaf is limited by the stops 27 which stop said leaf at its extended position at a point clear of and adjacent the outer edge of the table top, so that upon release of the top to its normal horizontal position the top and extension leaf are in substantially contacting relation at their proximate edges and form a continuous table top. Tilting

of the opposite side of the top in the same manner then releases and automatically projects the opposite leaf into operative extended position and the table top then rests upon the inner ends of bars 23 in substantially the same plane as the extension leaves, the relative position of the leaves and top being maintained by the engagement of bars 23 with the T-shaped guide members 15.

The top is effectively prevented from excessive tilting relative to the frame by the headed pins 20 whose head engages the guides 15 to limit said tilting movement; the apertures 21 in guides 15 through which said pins pass being of a size to permit the slight tilting of the pin therein. The combination of the V-shaped guide blocks 28 and the pins 29 serves to guide the tilting movement of the top and to prevent simultaneous equal upward movement of all parts of the top relative to the frame. Upon tilting of the top the hook portion 30 of pin 29 is swung clear of the bottom of the block 28 and engages the upwardly outwardly inclined sides of said block whose inclination permits continued tilting of the top as is required to release the extension leaf from its nested position beneath the top. Upon direct upward application of force to the table top in a manner tending to simultaneously equally move all parts of the top relative to the table frame, the hook portion 30 of pin 29 engages the under side of the block and prevents movement of the top relative to the frame. Thus it is made possible to centrally grasp the table top to carry the table without causing tilting or other movement of the top relative to the frame, and it is not necessary for the frame itself to be grasped as would otherwise be necessary in a table of this construction having no fixed connection between the table top and table frame.

The invention having been set forth, what is claimed as new and useful is:

1. In combination, a table frame, a table top shiftable relative to said frame, an extension leaf slidable relative to said frame, means carried by said top for normally holding said leaf therebeneath, and means for urging said leaf to extended position upon release of said leaf by an upward movement of the top.

2. In combination, a table frame, a table top shiftable relative to said frame, an extension leaf slidable relative to said frame, means carried by said top for normally holding said leaf therebeneath, and a spring cooperating with said leaf adapted to project said leaf to extended position upon release thereof by a movement of said top.

3. In combination, a table frame, a table top shiftable relative to said frame, flanges depending from the perimeter of said top, an extension leaf slidable relative to said frame and normally nested within said

flanges beneath said top, and means for projecting said leaf to extended position upon shifting of said top to release said leaf from nested position therein.

5 4. In combination, a table frame, a table top shiftable relative to said frame, flanges depending from the perimeter of said top, an extension leaf slidable relative to said frame and normally nested within said flanges beneath said top, and a spring co-operating with said leaf adapted to project said leaf to extended position upon shifting of said top to release said leaf from nested position therein.

10 5. In combination, a table frame, a table top shiftable relative to said frame, an extension leaf slidable relative to said frame, means carried by said top for normally positioning said leaf in retracted position beneath said top, and means for projecting said leaf to extended position upon shifting of said top to release said positioning means.

15 6. In combination, a table frame, a table top shiftable relative to said frame, a member carried by said frame having outwardly upwardly inclined sides, and a member carried by said top and cooperating with the inclined sides of said first named member to guide the movement of said top relative to said frame and limit said movement to tilting of said top.

20 7. In combination, a table frame, a table top shiftable relative to said frame, a V-shaped block carried by said frame, and a pin depending from said top and having a perpendicularly bent portion disposed beneath said block and adapted to engage one of the inclined sides of said block to tilt said top upon movement of the top relative to the frame.

25 8. In combination, a table frame, a table top shiftable relative to said frame, an extension leaf slidable relative to said frame and normally held in retracted position beneath said top, and guide means controlling the movement of the top relative to said frame to tilt said top toward one of its ends to release said leaf.

30 9. In combination, a table frame, a table top shiftable relative to said frame, a pair of extension leaves slidable relative to said frame, means carried by said top for normally locking said leaves thereunder, and guide means cooperating with said frame and top to tilt said top toward either of two of its ends when said top is shifted relative to said frame to release the means locking one of said leaves.

35 10. In combination, a table frame, a table top shiftable relative to said frame, an extension leaf slidable relative to said frame, means carried by said top for normally positioning said leaf in retracted position, means for projecting said leaf to extended position upon release of said positioning means, and

means guiding the movement of said top relative to said frame to release said positioning means, said guide means preventing simultaneous substantially equal upward movement of all points of said top relative to said frame.

40 11. In combination, a table frame, a table top vertically shiftable relative to said frame, a member fixedly carried by said frame at the center thereof, and a hook depending from said top and normally engaging said member to prevent shifting of said top, said hook being shiftable to avoid said member to permit selective tilting of either end of said top relative to said frame.

45 In testimony whereof I affix my signature.

OAK LANDAW.
